UNITED STATES PATENT OFFICE.

DAVID E. HUNTER, OF MUSKEGON, MICHIGAN, ASSIGNOR TO THE SHAW-WALKER CO., OF MUSKEGON, MICHIGAN, A CORPORATION OF MICHIGAN.

FURNITURE-TOP CONSTRUCTION.

Application filed January 30, 1925. Serial No. 5,691.

To all whom it may concern:

Be it known that I, DAVID E. HUNTER, a citizen of the United States of America, and a resident of Muskegon, Michigan, have invented a certain new and useful Improvement in Furniture-Top Constructions, of which the following is a specification.

This invention relates to improvements in furniture top construction, and more particularly to a novel construction for the tops of desks, tables, and like articles of furniture having a flat top, and while its use is not restricted to any type or design of furniture it is especially desirable in metal office furniture, such as desks or tables.

In the making of metal desks, as well as wood desks, a recent innovation has been the use of linoleum or similar composition as the surface material, the same being laid over a sheet metal plate or wood core. It is customary to carry the linoleum only to the edge of the plate or case, and to finish the edge with a band of wood or metal, or in the case of a metal desk, to flange the edge of the case plate to form the sides of the top. In metal desks particularly, there appears to be an objection to exposed metal about the edges about the top of a desk, which is explained by the fact that a person has a natural distaste for cold objects, and this is the reaction when placing the hand on or in contact with the metallic edge of a desk. Moreover, the ordinary construction presents the square edges and sharp corners that have always been common in office furniture, partly due to the fact that it is less expensive and partly due to a tendency toward plainness in furniture of this type, when as a matter of fact, rounded edges and corners not only enhance the appearance, but remove the objection of sharp corners and the attendant results of collision with persons and objects.

The purpose of the present invention is, therefore, to provide an improved construction for furniture tops and I have illustrated in the accompanying drawings a preferred embodiment in the form of a desk top for a flat top metal desk.

50 In the drawings,

Figure 1 is a perspective view of one corner of a desk or table top, giving a general idea of the construction.

Figure 2 is a view in vertical section through the corner of the top as taken on line 2-2 of Figure 1.

Figure 3 is a view in horizontal section taken on line 3-3 of Figure 1.

Figure 4 is a view in vertical section at any point along the edge and between corners of the top, such as at 4-4 of Figure 1.

Figure 5 is a plan view of one corner section of the linoleum as cut to fit around the edge of the core.

Figure 6 is a perspective view of one corner of the metal core before the linoleum is applied.

Figure 7 is a perspective view of the corner gusset plate.

Figure 8 is a perspective view of one of the corner caps.

Figure 9 is a perspective view of a corner of the top with portions broken away to show the construction, and

Figure 10 is a sectional view of a modified construction differing only in that a wood core is used.

In a metal desk, it is preferred to use a metal foundation or plate 1, which is suitably secured on the remaining part of the desk. The top, therefore, is a rectangular piece of sheet metal of relatively light gauge, with the marginal portions bent or shaped to form rounded edges 2, semi-circular in cross section. In the blank, the plate would be greater in dimension than the top of the desk to allow for the rounded edges or flanges which form the sides of the desk top. Moreover, the corners of the blank plate are cut away, to form right angled notches 3 at each corner. Over the plate is laid a layer 4 of linoleum, or other suitable composition fabric this material being cut to a pattern of substantially the same outline as the blank of the plate, with the corners cut away as at 5, in Figure 5. Cement or other adhesive is used for applying the material to the core 1, the marginal portions thereof being carried around the semi-circular flanges 2 and cemented thereto with its edges terminating substantially flush with the edges of the core.

The corners of the top are preferably treated by covering the notches by means of metal corner caps 6, of substantially the same sectional contour as the plate 1, with

its covering of linoleum 4. For reasons presently to be pointed out, and as shown in Figure 2, the corner caps vary in thickness from the underside, gradually decreasing in thickness as the upper edge is approached, so that the top side is relatively thin. Moreover, the contour of the corner caps as they appear in top plan view, has a rounded outer edge, such as would be described on an arc taken at the intersections of the prolongations of side edges. The method of applying the corner caps to the top after the covering has been applied will be understood from the following:

15 At the corners of the core plate 1, and on the top surface of the inturned flanged portions where they come together or are mitered, are triangular gusset plates 7, which are spot welded in place, the apex of these plates projecting diagonally into the notches at the corners. At the lower edge of each corner cap is a tongue-like projection 8 extending diagonally inwardly and lying against the underside of the flanges of the plate and beneath the extended end of the gusset plate 7. Passing upwardly through the tongue is a flat headed screw 9, with its head countersunk therein, which passes through a hole 7^a tapped in the gusset plate just above. By tightening the screw, the corner plate is drawn tightly and flush up to the corner. Before doing this, however, the corner edges of the linoleum are prepared to receive the cap. It will be observed that the side edges of the corner caps, slightly overlap the corresponding edges of the metal plate at the corners, thus affording a foundation against which the cap can be tightly drawn. The linoleum by preference is not brought up flush with the edges of the plate, but is beveled or slightly undercut so that a portion of the linoleum extends between the edges of the cap and the adjacent edges of the core plate. Hence, after the corner caps have been fitted in place, the edges of the linoleum are trimmed in the manner described, so that the caps are practically inlaid flush with the surface of the linoleum, and by tightening the screws from beneath, the caps are drawn down tightly into place, thus producing a perfectly smooth surface on the top and edges of the desk or table top. In like manner, the underside of the linoleum is cut or trimmed so as to come up flush with the diagonally extending tongue 8 thereof, these being in the form of triangular notches 10 along the mitered edges as shown in Figure 3.

For the purpose of appearance, the top edges of the caps are not brought to a point, but are cut somewhat diagonally along a concave or curved line at 11, the linoleum being trimmed to follow this curved line. Similarly the core plate may also be formed 65 to provide a curved or oblique corner at the

apexes of the corner notches 3 and 12 to correspond with the treatment of the points of the corner caps just above.

These corner caps may also be of material other than metal, but are preferably of bronze or the like and not only serve to make the desk top ornamental, but are essential to the construction in that they permit the rounded corner as well as the rounded edge to be curved out, and at the same time offer a protection to the linoleum at these exposed points. It is conceivable that the linoleum might be carried over the edges and brought together at the corners, but being non-elastic it would be quite impossible to work it into the double curved formation that would be necessary to give the corners a round contour in vertical section as well as in plan.

As clearly shown in Figure 10, a core 13 of wood may be used in place of the sheet metal core formed as heretofore described. In this construction the core would be solid and preferably of a multi-ply formation. The edges would be similarly rounded and the corners cut off but with sufficient material retained to provide an anchorage for the corner caps.

Having set forth the novel features of my construction, I claim as my invention:

1. A top for furniture comprising a core, a sheet of covering material laid over said core with its marginal portion extending around and beneath the edges thereof, and caps secured at the corners of said core and extending around the corner edges and inlaid flush with the edges and top surface of the covering material.

2. A top for furniture comprising a core having rounded edges, a sheet of covering material laid over said core with its marginal portion extending around and beneath the edges thereof, and corner caps of rounded conformation fixed to said core and extending around the corners and inlaid flush with the edges and top surface of the covering material.

3. A top for furniture comprising a flat rectangular core, having portions cut away at the corners, a sheet of pliable covering material over the top surface of the core and having its marginal portions carried around and secured beneath the edges thereof, and corner caps of non-pliable material anchored to the core and extending around the corner edges, the covering material being cut away at the corners to lie flush with the edges of said corner caps.

4. A top for furniture comprising a flat rectangular core, having its corner portions cut away, and rounded edge portions adapted to extend beyond the body of the article of furniture, a sheet of pliable covering material laid over the top surface of the core and having its marginal portions carried around and secured beneath the edges there-

of, and corner caps of non-pliable material anchored to the underside of the core at the corners thereof, and extending around and over the corner edges, the covering material 5 being cut away at the corners to lie flush with the edges of said corner caps.

5. A top for furniture comprising a core of sheet material formed with rounded in-turned flanges about the side edges, and 10 notches at the corners, a sheet of pliable covering material laid over the surface of said core, its marginal portions being bent around the edges thereof with its edges terminating substantially flush with the 15 edges of said in-turned flanges, and corner caps fitting over the corners of said core and anchored to the underside of said in-turned flanges thereof, said covering material being trimmed at the corners to lie 20 flush with the edges of said caps.

6. A top for furniture comprising a core of sheet material formed with inturned marginal flanges, a sheet of pliable covering material laid over the surface of said core, its 25 marginal portions being carried around the edges thereof with its edges terminating flush with the edges of said in-turned flanges, and corner caps anchored to the underside of said in-turned flanges, the corner portions of said covering material being 30 trimmed to lie flush with the edges of said caps.

7. A top for furniture comprising a core of sheet material shaped to form rounded 35 in-turned marginal flanges and right angled notches at each corner, a sheet of pliable

covering material over the surface of said core, its marginal portions being bent around the edges thereof with its edges terminating flush with the edges of said in-turned flanges, and corner caps fitting over the corner notches of said core and provided with extended portions lying flatwise against the underside of said flanges, screws passing through said extended portions and anchored in said flanges, the covering material 40 being trimmed to conform with the contour of said caps and to provide flush surfaces at their edges.

8. A top for furniture comprising a core of sheet material shaped to form rounded in-turned flanges about the side edges, and notches at the corners, a sheet of pliable covering material laid over the surface of said core, its marginal portions being bent 50 around the edges thereof with its edges terminating flush with the edges of said in-turned flanges, and corner caps fitting over the corner notches of said core and provided with tongues extending beneath the 55 flanges of said core in flatwise contact therewith, gusset plates fixed to said flanges at the corners, screws passing through said tongues and anchored in said plates, said plates extending around and over the edges of said core, and the covering material trimmed to 60 conform with the contour of said caps to provide flush surfaces at their contacting edges.

Signed at Muskegon this 24th day of January, 1925. 70

DAVID E. HUNTER.
